Inventor:
E. E. Goold,

C. C. Hines,
Attorney.

UNITED STATES PATENT OFFICE.

EVERETT E. GOOLD, OF VICTOR, COLORADO, ASSIGNOR OF ONE-HALF TO CORNELIUS H. VAN TILBORG, OF VICTOR, COLORADO.

AUTOMOBILE THROTTLE-LEVER LOCK.

1,356,863.

Specification of Letters Patent. Patented Oct. 26, 1920.

Application filed October 4, 1919. Serial No. 328,410.

To all whom it may concern:

Be it known that I, EVERETT E. GOOLD, a citizen of the United States, residing at Victor, in the county of Teller and State of Colorado, have invented new and useful Improvements in Automobile Throttle-Lever Locks, of which the following is a specification.

This invention relates to an automobile lever lock, and particularly to a lock for the throttle or gasoline-supply-controlling levers of automobiles.

The object of the invention is to provide simple, reliable and efficient means for locking the throttle lever in cut-off position, which lock can be released only by a person having a proper key.

The invention consists of the features of construction, combination and arrangement of parts hereinafter fully described and claimed, reference being had to the accompanying drawing, in which:—

Figure 1 is a plan view of the segment and spark and throttle levers of an automobile power mechanism, showing the application of the invention.

Fig. 2 is a section taken substantially on line 2—2 of Fig. 1.

Referring to the drawing, 1 designates the throttle and spark lever segment of an automobile power mechanism, said segment including the arcuate member or plate 2, and 3 and 4 respectively designating the spark and throttle levers, the said levers being 35 pivotally supported at their inner ends in the usual manner. As shown, the lever 3 is connected with a sleeve 5 which encircles a rod 6, to which the inner end of the lever 4 is connected, said sleeve and rod being concentrically journaled in the usual steering 40 post (not shown) of the vehicle.

The lever 4 has its outer end portion 7 projecting across and beyond the upper surface of the plate 2 and provided with an 45 actuating knob or finger piece 8, whereby said lever may be adjusted along the curved plate to different positions for rotating the rod 6 to control the feed of the motive fluid to the carbureter.

50 The lever 4 is provided with an expanded portion 9 having an opening 10 formed therein to receive a rotary tumbler 11 of a lock mechanism, the latter being preferably of the pin type, said tumbler being provided 55 with a key receiving slot or passage 12 of

suitable form. The lock mechanism is arranged within a casing 13, formed upon or secured to the underside of the expanded portion 9, and said lock mechanism includes a bolt 14 adapted to be actuated by 60 the rotation of the tumbler 11 through the medium of the inserted key.

The bolt 14 is adapted when in retracted position to have its outer end lie inwardly of the inner edge of the plate 2, thus allowing the lever 4 to be adjusted freely over said plate without interference from the lock mechanism for the purpose of controlling the feed of the motive fluid in the usual way in the running of the car. The bolt is 70 adapted to be projected by the rotary movement of the tumbler to engage a locking notch or recess 15 formed in the inner edge of the plate 2. This locking notch or recess is so disposed that when the lever 4 is 75 in cut-out position the bolt may be projected to engage the recess 15 and thus lock the lever in such position, so that it can not be moved and hence the feed mechanism will be rendered inoperative for the supply of 80 gasoline to the motor.

It will thus be understood that in practice the owner or operator of the vehicle may employ the throttle lever in the usual manner so long as it is free from locking 85 engagement with the segment, but that the lever may be locked in cut-off position when the machine is standing or placed in the garage so as to prevent any one, except a person provided with a proper key, from releasing the lever for manipulation, thus preventing surreptitious use of the vehicle. It will be evident from the foregoing that the outer end of the lock casing 13 moves in 90 guiding contact with the inner edge of the plate 2, while the end 7 of the lever 4 moves in guided contact with the upper surface of said plate, thus guiding the lever for movement in a true path. The lock casing is preferably provided with a lip or projection 95 16 to extend under and ride in contact with the lower face of the plate 2, thus further insuring the accurate guiding of the lever in its movement and preventing the lever from being sprung upwardly when locked 105 and thus obviating any liability of the projected bolt 14 being withdrawn from engagement with the notch 15 through such expedient. It will be observed that the construction is simple and inexpensive and of 110

such a character as to be applied to existing types of throttle levers and segments.

Having thus fully described my invention, I claim:

- 5 The combination with a power control mechanism for automobiles, of a segment having a locking notch formed at the off position thereon, a throttle lever having a pivoted inner end portion, an outer end portion forming a handle overlying said segment and in sliding contact therewith, and an expanded intermediate portion, a lock casing secured to the under face of said expanded intermediate portion of said
- 10

throttle lever and including a sliding bolt 15 for engagement with the notch in said segment, and a rotary key-actuated tumbler, said tumbler being projected into an opening formed in the expanded portion of said throttle lever, and a projection carried by 20 said lock casing and underlying the segment and coöperating with the outer end portion of said lever for maintaining the latter accurately in its path of travel to and from the off position aforesaid.

25 In testimony whereof I affix my signature

EVERETT E. GOOLD.
